LOOM HARNESS

John Jacob Kaufmann, Elkins Park, Pa., assignor
to Steel Heddle Manufacturing Company, Philadelphia, Pa., a corporation of Pennsylvania

Application November 19, 1948, Serial No. 60,908

4 Claims. (Cl. 139—92)

1

This invention relates to loom harness, and it relates more particularly to improved means, in a heddle frame, for securing the ends of the rods upon which the heddles are mounted.

Heretofore, various forms of devices have been used for the purpose of securing the rods upon which the heddles are mounted in loom harness frames. The most satisfactory forms of such devices were those which were mounted on the outer faces of the end struts of the frame.

However, while it has long been recognized that it is advisable, principally for safety as well as for other purposes, to keep the outer faces of the end struts of the frames free from projections and devices which tend to catch the hands of the weavers as well as becoming fouled on other objects, it has been found difficult to provide a satisfactory securing device on the inside of the end struts of the frame.

The principal object of the present invention is to provide, in a loom harness heddle frame, improved means for securing the ends of the heddle rods, which means are disposed entirely within the interior of the frame.

A further object of the present invention is to provide a device of the character aforesaid which may be pivotally mounted so that the same may be swung outward to disengage it from the end of the heddle rod.

A further object of the present invention is to provide a device of the character aforesaid with novel locking means which will effectively prevent the accidental disengagement of the securing device from the end of the heddle rod.

The nature and characteristic features of the invention will be more readily understood from the following description, taken in connection with the accompanying drawing forming part hereof, in which:

Figure 1 is a front elevation of a loom harness heddle frame provided with heddle rod securing devices embodying the main features of the present invention;

Fig. 2 is an enlarged section thereof taken on the line 2—2 of Fig. 1;

Fig. 3 is a perspective view of one corner portion of the heddle frame, illustrating more particularly the device of the present invention in its relationship with other parts of the frame; and

Fig. 4 is a perspective view of the securing device of the invention detached from the frame.

It should, of course, be understood that the description and drawing herein are illustrative merely, and that various modifications and

2

changes may be made in the structure disclosed without departing from the spirit of the invention.

Referring to the drawing, the heddle frame proper may be of any preferred construction, for example, the same may comprise top and bottom rails 10 connected by end struts 11. The end struts 11 may be of a composite character consisting of central wooden strips 12, having metallic strips 13 and 14, respectively, mounted on the inner and outer faces of said wooden strips 12. The ends of the metallic strips 13 and 14 are bent over and secured to the inner and outer edges, respectively, of the top and bottom rails 10 in the usual manner.

The heddle supporting rods 15 may be of any preferred type, comprising strips of flat metal which extend from end to end of the frame. The ends of the heddle supporting rods 15 are normally seated in slots 16 extending through the end struts 11. The heddle supporting rods 15 are preferably of such length so as not to project beyond the outer faces of the metallic strips 14 of the end struts 11.

25 The heddles 36 are mounted on the heddle rods 15 in any preferred manner as it will be apparent that the device of the present invention is applicable to various types of harness frames, and for the securing of various types of heddle rods in such frames.

25 Each of the heddle rods 15 is provided near each end with an aperture 17 adapted to be engaged by a portion of the securing device as will be hereinafter more fully set forth.

35 The securing device of the present invention is preferably made of thin flat spring metal punched and formed to provide the several component parts thereof. The same is secured to the inner face of the metallic strip 13 of the end strut 11 by means of a rivet 18, upon which it is pivotally mounted. The device has an arm 19 extending from the pivotal portion and is cut away on one side to provide a recess 20 into which a prong 21 projects. The arm portion 19 also has an extension 22 beyond the prong 21 which is curved at the free end to facilitate manual engagement thereof for the purpose of manipulation.

50 The aperture 17 near the end of the heddle rod 15 is engaged by the prong 21 when the securing device is in its normal operative position, and the tension of the arm 19 will not only serve to stress the heddle rod to hold the same taut, but 55 will also serve to maintain the end of the heddle

rod in the recess or slot 16 in which it is normally seated.

Oppositely disposed with respect to the main arm 19 of the securing device is another arm 23 having an inwardly extending lug 24 formed on the end thereof by bending the same. This lug 24 normally engages an aperture 25 in the strip 13 of the end strut 11.

When the securing device is in its normal operative position the arm 19 is stressed to maintain the heddle rod 15 taut and, also, to maintain the end of the heddle rod 15 within its slot 16.

When it is desired to disconnect one end of a heddle rod for the purpose of removing or adding heddles, the arm 19 at that location will be swung sidewise on its pivot which will cause the lug 24 at the free end of the arm 23 to be disengaged from the aperture 25 in the metallic strip 13, whereupon the prong 21 may be disengaged from the aperture 17 in the end portion of the heddle rod.

When the securing device at one end of a heddle rod is thus disengaged therefrom the similar device at the other end of the said rod will, by reason of the normal stress thereof, move the heddle rod lengthwise a sufficient distance to permit the end thereof to be freed from the slot 16 so that additional heddles may be mounted on the heddle rod at that end, or if desired some of the heddles may be thus removed.

I claim:

1. In a loom harness heddle frame comprising top and bottom rails connected by end struts and having heddle supporting rods mounted therein, the means for securing the heddle supporting rods in the frame comprising thin flat metal spring members pivotally mounted intermediate their respective ends at fixed locations on the end struts, said spring members each having a normally stressed arm portion flexible in its axial plane but substantially rigid in a plane transverse to its axis and with a part normally in engagement with the end portion of the heddle supporting rod but adapted to be swung sidewise on its pivotal axis out of the plane of the heddle rod and thus be disengaged from the end portion thereof, and another flexible arm portion on the other side of the pivot having a part engaging a part of the end strut when the securing member is in the operative position thereby serving to hold the spring member normally against pivotal movement but adapted to be released from such engagement to permit the sidewise movement on the pivotal axis.

2. In a loom harness heddle frame comprising top and bottom rails connected by end struts and having heddle supporting rods mounted therein, the means for securing the heddle supporting rods in the frame comprising the provision of slots in the end struts in which the ends of the heddle supporting rods are normally seated, and thin flat metal spring members pivotally mounted intermediate their respective ends at fixed locations on the end struts, said spring members each having a normally stressed arm portion flexible in its axial plane but substantially rigid in a plane transverse to its axis and with a part normally in engagement with the end portion of the heddle supporting rod but adapted to be swung sidewise on its pivotal axis out of the plane of the heddle rod and thus be disengaged from the end portion thereof, and another flexible arm portion on the other side of the pivot

having a part engaging a part of the end strut when the securing member is in the operative position thereby serving to hold the spring member normally against pivotal movement but adapted to be released from such engagement to permit the sidewise movement on the pivotal axis.

3. In a loom harness heddle frame comprising top and bottom rails connected by end struts and having heddle supporting rods mounted therein, the means for securing the heddle supporting rods in the frame comprising the provision of slots in the end struts in which the ends of the heddle supporting rods are normally seated, and thin flat metal spring members pivotally mounted intermediate their respective ends at fixed locations on the inside faces of the end struts, said spring members each having a normally stressed arm portion flexible in its axial plane but substantially rigid in a plane transverse to its axis and with a part normally in engagement with the end portion of the heddle supporting rod but adapted to be swung sidewise on its pivotal axis out of the plane of the heddle rod and thus be disengaged from the end portion thereof, and another flexible arm portion on the other side of the pivot having a lug engaging an aperture in the end strut when the securing member is in the operative position thereby serving to hold the spring member normally against pivotal movement but adapted to be released from such engagement to permit the sidewise movement on the pivotal axis.

4. In a loom harness heddle frame comprising top and bottom rails connected by end struts and having heddle supporting rods mounted therein, the means for securing the heddle supporting rods in the frame comprising the provision of slots in the end struts in which the ends of the heddle supporting rods are normally seated, and thin flat metal spring members pivotally mounted intermediate their respective ends at fixed locations on the inside faces of the end struts, said spring members each having a normally stressed arm portion flexible in its axial plane but substantially rigid in a plane transverse to its axis and provided with a prong engaging an aperture in the end portion of the heddle supporting rod, each of said spring members being adapted to be swung sidewise on its pivotal axis out of the plane of the heddle supporting rod and thus free the aforesaid prong from engagement with the aperture in the end portion of the heddle supporting rod, and another flexible arm portion on the other side of the pivot having a lug engaging an aperture in the end strut when the securing member is in the operative position thereby serving to hold the spring member normally against the pivotal movement but adapted to be released from such engagement to permit the sidewise movement on the pivotal axis.
